CLAIM

The ornamental design for a painter's service cart, as shown and described.

DESCRIPTION

FIG. 1 is a perspective view of a painter's service cart showing my new design, with the cart fully extended and the cover element in a vertical position;

FIG. 2 is a front elevational view thereof, with the cart partially retracted and the cover element in a horizontal position;

FIG. 3 is a front elevational view thereof, with the cart fully retracted and the cover element in a vertical position;

FIG. 4 is a right side elevational view of FIG. 3;

FIG. 5 is a left side elevational view of FIG. 3;

FIG. 6 is a top plan view of FIG. 3;

FIG. 7 is a bottom plan view of FIG. 3; and

FIG. 8 is an enlarged sectional view taken on the line 8—8 in FIG. 4.

The rear elevation of the painter's service cart is the mirror image of the front elevation.
